(57) **CLAIM**

The ornamental design for a pistol grip, as shown and described.

DESCRIPTION

FIG. 1 is an isometric view of an embodiment of a pistol grip according to my design;

FIG. 2 is another isometric view thereof;

FIG. 3 is front view thereof;

FIG. 4 is a rear view thereof;

FIGS. 5 and 6 are side views thereof;

FIG. 7 is a top view thereof;

FIG. 8 is a bottom view thereof;

FIG. 9 is an isometric view of an embodiment of a pistol grip according to my design;

FIG. 10 is another isometric view thereof;

FIG. 11 is front view thereof;

FIG. 12 is a rear view thereof;

FIGS. 13 and 14 are side views thereof;

FIG. 15 is a top view thereof; and,

FIG. 16 is a bottom view thereof.

Broken lines having repeated short dashes in the Figures are for illustrative purposes only and form no part of the claimed design. Shade lines having a combination of long and short lines in the Figures show contour and not surface ornamentation.
